HANDBAG

Willie Mae Kanzow, Knoxville, Tenn.

Application May 29, 1940, Serial No. 337,891

4 Claims. (CL. 150—10)

This invention relates to hand bags, purses, laundry bags and the like and more especially to an article of this type having means associated therewith for automatically closing the same. More specifically, the invention relates to a flexible bag having the opposed sides of its opening removably attached to adjacent turns of a coiled wire. The coiled wire also serves as a handle and due to the natural tendency for the turns or convolutions to rest against each other in contracted position, it is evident that the attached sides of the bag opening will normally remain in closed position.

It is therefore, an object of this invention to provide a hand bag, purse or the like, comprising a flexible bag having the opposed sides of its opening removably attached to adjacent turns of a coil spring handle. In the present showing of the invention, there are about one and one-third turns in the coiled spring handle, therefore, the overlapping ends extend approximately one third of the circumference of the spring and have mounted thereon the opposed edges of the bag opening. This type of construction permits the bag to be easily attached or removed from the handle and when once attached, it will not become detached of its own accord. Furthermore, the coiled spring has the necessary resiliency to permit the bag to be opened as widely as desired, but when the sidewalls are released the bag will return to closed position.

Some of the objects of the invention having been stated, other objects will appear as the description proceeds, when taken in connection with the accompanying drawings, in which—

Figure 1 is an elevation of my improved handbag;

Figure 2 is a vertical sectional view taken along the line 2—2 in Figure 1;

Figure 3 is an isometric view of the flexible container or bag portion as it appears, prior to being inserted upon the handle;

Figure 4 is an isometric view of the handle apart from the bag portion;

Figure 5 is a sectional detail view taken along the line 5—5 in Figure 4;

Figure 6 is a plan view of Figure 1 showing the bag in closed position;

Figure 7 is a plan view similar to Figure 6 but showing the bag in an opened position;

Figure 8 is a view showing a slight modification of the hand-bag handle structure showing a detachable point for use when inserting a bag on the handle;

Figure 9 is a sectional view showing the point 55

removed and a ball inserted over the end of the handle.

Referring more specifically to the drawings, the numeral 10 denotes a suitable flexible bag or container which is formed from any suitable material such as cloth, leather or the like. The bag is constructed by taking a rectangular piece of material and sewing the side edges together along seam lines 11, leaving gaps or slits 12 near the open end. The open end of the bag 10 has seamed edges 14 and 15, said edges constituting opposed sides of the opening of the bag. If desired the edges may be pinked or in case material is used that does not fray, raw edges may be provided. Figure 3 shows the bag structure in the position that it assumes prior to being inserted upon a suitable handle.

Figure 4 shows the type of handle employed for the bag shown in Figure 3. This handle comprises a coiled wire 17 having its ends overlapping each other. These ends may be pointed so that they can easily penetrate suitable balls, knobs or other ornaments 18, which are made of sponge rubber and serve to prevent the container from becoming detached.

When it is desired to assemble the bag and handle, it is necessary to remove the balls 18 from the sharpened ends of coiled wire 17. Then the pointed ends of the wire 17 are laced through the upper opposed edges 14 and 15 of the bag 10. It is necessary, however, to pleat the upper edges of the bag so that the sharpened ends of the wire 17 will penetrate a series of overlapping pleats or folds 20 and 21. Therefore, when the two opposed sides 14 and 15 of the bag 10 are pleated and penetrated by the ends of the coiled wire 17, the whole bag will assume a substantially circular or half moon appearance as shown in Figure 1. The shape of the handle causes the bag to assume this position. After the ends of the wire 17 have been properly installed, the balls 18 are again placed on the ends of the wire to prevent the bag from becoming detached. Since the coiled wire has an inherent resiliency therein, tending to cause the overlapping portions to rest against each other, it is seen that the balls 18 will each contact an adjacent turn in the wire 17 and be normally held in such contact by virtue of this resiliency. Therefore, when the coiled wire 17 is in a normal position, the upper end of the bag 10 will be closed in the manner shown in Figures 2 and 6. This type of construction eliminates the necessity of sewing the handle to the bag or of providing perforations for the wire to go through. It also elimi-

nates unnecessary hemming or facing to accomplish this purpose.

In order that means be provided whereby the bag may be releasably held in opened position, a suitable bar 25 has been pivoted as at 26 to one of the turns of the handle member 17. This bar is slidably mounted on the handle and can be inserted thereon between the fabric folds when the edges of the bag are laced on the ends of the arcuate wire. The lower end of the bar 25 has a forked portion 27 which is adapted to engage the adjacent turn in the coiled wire 17 in the manner shown in Figure 7 when it is desired to hold the bag in opened position.

It is often desirable to eliminate sharp points or ends on the handle structure to prevent injury, especially where the balls 18 are made of soft material and are easily detached. On the other hand, a sharp point is necessary when inserting a bag on the handle.

Figure 8 shows the end of a handle 17a with a restricted end portion 17b integral therewith, the other portions of the handle being identical to handle 17. A pointed member 30 removably fits over portion 17b when a bag is being inserted on the handle, said pointed member also being adapted for initially punching the balls 18 prior to the same being inserted thereon. After inserting the bag on the handle and after initially punching the balls, the points 30 are removed from the ends of the handle, leaving the blunt restricted ends 30 exposed. Then these blunt ends are inserted in the punches in the balls 18 as shown in Figure 9. This type of construction eliminates the possibility of injury to the users of the bag on account of sharp points associated with the handle.

Other outstanding advantages of the present invention are as follows: First, the spring resiliency in the handle 17 closes the bag automatically thereby eliminating the necessity of some sort of hinge for opening and closing and also eliminating the necessity for a fastener to keep the bag closed. Second, the handle is unbreakable, easily kept clean, and will not become detached from the bag or purse as handles often do on other types of conventional bags. Third, this handle can be made round, oval, square or triangular, as long as the overlapping portions which are laced through the bag remain in such a position as to give the proper resiliency necessary to normally keep the bag closed. Fourth, upon detaching the handle from the bag, the bag portion will assume a rectangular shape which can easily be made without much workmanship, or loss of material in cutting, due to irregularities in shape. The combination also provides an artistic half moon shape which is desirable. Without this handle, the half moon shape can only be obtained by cutting in that shape. Fifth, washing of the bag will be greatly simplified by the simple method of detaching and attaching the handle. Sixth, the handle can be plated with chromium, nickel, silver, gold or the like so that the bag can have the necessary ornamental appearance. If desired, a stiff cover can be made for the handle out of any suitable material such as rubber, cloth, leather with the corresponding ornaments attached, without departing from the spirit of the present invention. Seventh, the

rubber balls 18 serve to prevent the handle from slipping through the bag by adhering to the metal through suction, as well as serving as ornaments. In this way the necessity of having special devices for holding knobs or other materials to the handle is eliminated. Eighth, when the bag handle is used in connection with a sewing bag, the knobs or balls 18 serve as a needle or pin cushion, and at the same time prevent the needle points from rusting. The rubber knobs are also silent, and do not mar or scar furniture. Ninth, if desired, the handle can be laced through the bag at various distances from the bag top, thereby making the bag shallow or deep, which features make it possible to adjust the capacity of the bag.

In the drawings and specifications there has been set forth a preferred embodiment of the invention, and although specific terms are employed, they are used in a generic and descriptive sense only and not for purposes of limitation, the scope of the invention being set forth in the appended claims.

I claim:

1. A handbag comprising a flexible container having an opening and a spring steel looped member having its ends overlapping each other and occupying parallel positions and extending in opposite directions and having an inherent resiliency to press the overlapping ends towards each other, the overlapping ends being secured to the container on opposite sides of the opening, whereby the looped member serves as a handle for the bag and the overlapping ends normally hold the opening in closed position.

2. A handbag having a handle formed from a spring steel looped member having overlapping ends occupying a parallel relation to each other and projecting in opposite directions, a flexible container having an opening therein, each of said overlapping ends being secured to the container at a separate and opposite side of the opening.

3. A handbag comprising a flexible container having an opening therein and a bent resilient bar forming a complete loop and extending more than 360 degrees and having its ends overlapping and parallel to each other, and extending in opposite directions, said bar having an inherent tendency to press the overlapping ends towards each other and being secured to opposed sides of the container adjacent said opening, whereby the opening is held in normally closed position, and members mounted on the ends of said resilient bar for preventing the container from becoming detached.

4. A handbag comprising a flexible container having an opening therein, a bent resilient bar forming a complete loop and extending more than 360 degrees and having its ends overlapping and parallel to each other and extending in opposite directions, said ends being slidably secured to the bag on opposed sides of said opening, said bar having an inherent tendency to press the overlapping ends towards each other whereby the opening is held in normally closed position, and members mounted on the ends of said bar for preventing the container from becoming detached.

WILLIE MAE KANZOW.
